UNITED STATES PATENT OFFICE

134,179

DESIGN FOR A DECK OF PLAYING CARDS

Christian Frederik Nielsen, Reykjavik, Iceland

Application January 12, 1942, Serial No. 105,151

Term of patent 7 years

To all whom it may concern:

Be it known that I, Christian Frederik Nielsen, a subject of the King of Denmark and Iceland, residing at Styrimannastigur 10, in the city of Reykjavik, and State of Iceland, have invented a new, original, and ornamental Design for a Deck of Playing Cards, of which the following is a specification, reference being had to the accompanying drawing, forming part thereof, and in which:

Figures 1, 2, 3 and 4 are face views of certain picture cards of the deck, showing my new design.

The remaining picture cards vary only with respect to conventional pips; and the other cards of the deck are conventional.

I claim:

The ornamental design for a deck of playing cards, substantially as shown and described.

CHRISTIAN FREDERIK NIELSEN.
